UNITED STATES PATENT OFFICE.

ANDREW REESE, OF MASSILLION, OHIO.

WORKBASKET.

Application filed January 6, 1927. Serial No. 159,353.

This invention aims to provide a work basket or similar article which may be fashioned cheaply out of standard materials and present an ornamental appearance coupled with durability and trifling cost.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in top plan a device constructed in accordance with the invention;

Figure 2 is a transverse section.

Figure 3 is a plan showing a modified form of the basket;

Figure 4 is a transverse section of the basket shown in Figure 3;

Figure 5 is a fragmental section taken longitudinally of the flexible side wall of the basket.

The work basket shown in Figures 1 and 2 comprises a metal base 1 of cup-like frustoconical form, having at its upper edge an outstanding marginal flange 2 of annular form, the flange being supplied with a depending circumferential bead 3. Specifically, the base may be what is known commonly as a "pie tin."

The basket includes a body 4, generally made of wire and including an upper ring 5 and a lower ring or shoulder 6, the rings 5 and 6 being connected by uprights which are attached to the rings in any suitable way. Each upright comprises approximately parallel arms 8 and a head 9, of inverted V shape, or otherwise, joining the arms 8 of each upright at their upper ends. The heads 9 may be inclined outwardly, as shown at 10, to increase the capacity of the basket and, also, to protect, in some measure, a flexible wall 11, preferably made of cloth, and of annular form, the wall 11 being threaded across the arms 8 of the uprights, and passing in front of one arm and behind the next arm. The ring 6 is called a shoulder, be-

cause the flange 2 on the base 1 abuts against it. The lower ends of the arms 8 of the uprights are turned to form inwardly extended feet 12 that bear upon the under surface of the flange 2, within the bead 3, and hold the flange 2 against the shoulder-ring 6, the construction being such that an unusually secure attachment between the base 1 and the body of the basket is afforded, it being practically impossible for the base to become detached from the body, and dump the contents of the basket.

The base 1, the uprights and the flexible textile wall 11 may be colored or ornamented as desired, those details being matters of design, and left to the taste of the manufacturer, as contributing to the mercantable qualities of the article, without having any effect on its patentability.

It will be observed that the lower ring 6 prevents the wall 11 from sliding downwardly off the arms 8 of the uprights, the ring 5 preventing the wall from sliding upwardly off the arms of the uprights.

The work basket shown in Figures 3 and 4 comprises a metal base 21 of cup-like frustoconical form, having at its upper edge an upstanding marginal flange 22 of annular form, the flange being supplied with a depending circumferential bead 23. As hereinbefore explained, the base may be a "pie tin".

The basket includes a body 24, generally made of wire, and including an upper ring 25 and a lower ring or shoulder 26, the rings 25 and 26 being connected by uprights which are attached to the rings in any suitable way. Alternating ones of the uprights comprise parallel arms 27, spaced at a considerable distance apart, and a curved head 28 joining the arms 27. The remaining uprights embody downwardly diverging arms 29 and a head 30 joining the arms 29. The heads 30 are so narrow, and the arms 29 are disposed so closely together at their upper ends, that the upper extremities of the uprights 29-30 may be inserted into the hole of a spool of thread (not shown). In this form of the invention, the upper ends of the uprights are not outwardly inclined, as shown at 10 in Figure 2.

The ring 26 is called a shoulder, because the flange 22 on the base 21 abuts against it. The lower ends of the arms 27 and 29 of the uprights are turned to form inwardly extended feet 32 that bear upon the un-

der surface of the flange 22, within the bead 23, and hold the flange 22 against the shoulder-ring 26, the construction being such that an unusually secure attachment 5 between the base 21 and the body of the basket is afforded, it being practically impossible for the base to become detached from the body, thereby spilling the contents of the basket.

10 In this form of the invention, the flexible wall is in the form of a flattened tube 33, preferably made of cloth, one end of the tube being turned in, as at 34, to avoid a raw edge, and the opposite end of the tube 15 being inserted into the first-specified end, as shown at 35. Within the annular flattened tube is disposed a stiffener 36, the ends of which are joined as shown at 37, the width of the stiffener 36 being equal approximately to the distance between the 20 rings 25 and 26. The flexible wall of the basket is not threaded back and forth between the uprights, as in Figure 2, but the

wall, in annular form, is placed within the basket, outward movement of the wall being 25 prevented by the arms 27 and 29 of the uprights, upward movement of the wall being limited by the ring 25, and downward movement of the wall being limited by the ring 26. Owing to the presence of the stiffener 30 36, the flexible wall will remain in place, in the position shown in Figure 4, but by springing the wall inwardly, it may be removed from between the rings 25 and 26.

What is claimed is:—

In a basket of the class described, upper and lower rings, uprights joining the rings and having feet at their lower ends, a flexible wall held against outward movement by the uprights, and held by the rings 40 against movement longitudinally of the uprights, and a base the margin of which is located between the feet and the lower ring.

In testimony that I claim the foregoing as my own, I have hereto affixed my signature.

ANDREW REESE.
